(57) **CLAIM**

We claim, the ornamental design for an office perforator, as shown and described.

DESCRIPTION

FIG. 1 is a front perspective view of a office perforator, showing our new design;

FIG. 2 is a rear perspective view thereof;

FIG. 3 is a side elevational view thereof;

FIG. 4 is an opposite side elevational view thereof;

FIG. 5 is a front elevation view thereof;

FIG. 6 is a rear elevational view thereof; and,

FIG. 7 is a top plan view thereof.

Portions of the drawings shown in broken lines are for purposes of illustration only and form no part of the claimed design.
